UNITED STATES PATENT OFFICE

104,789

DESIGN FOR A LIGHTING STANDARD

James N. Locke, Long Beach, Calif.

Application October 26, 1936, Serial No. 65,494

Term of patent 3½ years

To all whom it may concern:

Be it known that I, James N. Locke, a citizen of the United States, residing at Long Beach, in the county of Los Angeles, State of California, have invented a new, original, and ornamental Design for a Lighting Standard, of which the following is a specification, reference being had to the accompanying drawing, forming a part thereof:

The figure is a side elevation of the lighting standard showing my new design.

The lighting standard is substantially symmetrical and therefore the side opposite to the side disclosed in the drawing is substantially the same in appearance.

I claim:

The ornamental design for a lighting standard, as shown and described.

JAMES N. LOCKE.
